BOAT

Roy M. Martindale, 14510 Flanders, Detroit, Mich.

Filed Nov. 25, 1960, Ser. No. 62,979

Term of patent 14 years

(Cl. D71—1)

FIG. 1.

FIG. 2.

The dominant features of my design reside in the portions thereof shown in full lines.

I claim:

The ornamental design for a boat, as shown and described.
